UNITED STATES PATENT OFFICE.

THOMAS A. BOYD AND HAROLD A. BOYD, OF GLASGOW, SCOTLAND.

DOFFING MECHANISM OF SPINNING, TWISTING, AND LIKE FRAMES.

1,369,613.

Specification of Letters Patent. Patented Feb. 22, 1921.

Application filed March 8, 1919. Serial No. 281,563.

To all whom it may concern:

Be it known that we, THOMAS ALEXANDER BOYD and HAROLD ARTHUR BOYD, subjects of the King of Great Britain, and residents 5 of Glasgow, Scotland, have invented certain new and useful Improvements in Doffing Mechanism of Spinning, Twisting, and like Frames, of which the following is a specification.

10 This invention relates to spinning, twisting and like frames in which the builder rails and also the step rails if such be used are lowered clear of the spinning spindles for the purpose of doffing full bobbins from 15 and placing empty bobbins upon the said spindles.

The primary object of our invention is to facilitate the lowering, raising and supporting of such rails and also to supporting of 20 the spindle against the lateral pull of its driving band when the said rails are lowered for doffing. In frames of the kind referred to the builder rail and the step rails, when such are used, are lowered and raised by a 25 doffing shaft which in some cases also serves the purpose of a traverse shaft. According to this invention the doffing shaft referred to is revolved in one direction to lower and in the opposite direction to raise the said 30 builder rails, and also the said step rails if such be used, by means of power obtained from the main driving belt of the frame when the said belt has been shifted from the fast to the loose pulley. The power is com- 35 municated by means of friction driving pulleys or disks driven by the main driving belt and communicating motion in one direction or another to a movable friction pulley which may be pressed against one of 40 the said driving pulleys or the other, or held in a neutral position. The power from the said movable pulley is communicated to the doffing shaft through a worm shaft and worm which drive a worm wheel on the 45 doffing shaft and which worm is adapted to be thrown into or out of mesh with the worm wheel when the said doffing shaft is used as a traverse shaft. Further, this invention includes an arrangement whereby 50 the chains which lower and raise the builder rails also raise the step rails when such are used. Still further, for frames in which step rails are used and are raised to working position after doffing, there is provided 55 for sustaining the step rails in position and releasing them from that position a locking

arrangement passing from end to end of the frame so as to be operated from one or both ends of the frame. The invention also includes a spindle support located above the 60 flier below the top spindle rail and behind the spindle. When the lateral spindle support in the builder rail or in the step rails is withdrawn, the spindle band draws the spindle against the support mentioned, thus 65 keeping the spindle sufficiently in central position to receive the empty bobbin after doffing.

Accompanying this specification are three sheets of drawing: Figures 1 and 1^A show 70 an end sectional view of the spindle rail, step and builder rail, doffing shaft and friction disk for driving same, also chain for lifting and lowering: Fig. 2 back balance of 75 step rail and step rail slide: Fig. 3 front view showing driving pulleys, driving and back end frames, traverse motion, doffing shaft and means of operating same, step rail socket and support builder rail slide: Fig. 4 back end frame, traverse motion, 80 pawl and ratchet to operate doffing shaft for traverse: Fig. 5 end view driving end frame, 85 cut away to show worm and worm wheel for doffing shaft, worm bracket and tumbler to lower worm out of gear: Fig. 6 plan view of Fig. 5.

In a practical application of our invention applied to a jute spinning frame Figs. 1 to 6 we mount on suitable framing a top spindle rail 1 disposed horizontally and 90 passing along the front side of the frame, a low and a top stay rail 2 and 3, vertical guide rods 4, placed at a suitable distance apart and supported on the low stay rail 2 and extending up to and supported by the 95 top spindle rail 1. On the vertical guide rods 4 are sockets 5 each with knees extending to the front and carrying a step rail 6. On the front side of each step rail 6 we mount in covers 7 a pair of builder slides 8 100 each having a horizontal limb 8^A extending inward for connection with a builder lifting chain 9 hereafter described. The lower end of each builder slide is guided in a guide bracket 10 bolted to the lower side of the 105 step rail 6. On the upper end of each builder slide 8 we mount a builder rail 11. On the framing we mount in bearings placed at suitable intervals a doffing shaft 12 ex- 110 tends from end to end of the frame parallel with the top spindle rail 1 and at a suitable distance below it. The said doffing

shaft 12 serves the double purpose of an oscillating traverse shaft to traverse the builder rails up and down and when disengaged from the traverse motion and geared to the lowering motion as hereafter explained, as a doffing shaft for lowering and raising the builder rails and step rails. On the said doffing shaft 12 opposite each builder slide we mount a builder chain pulley 13 with a builder chain 9 extending down to and fixed to the horizontal limb 8¹ of the builder slide 8 to operate the builder rail 11 during spinning and also to lower the builder rail for doffing. In the horizontal limb 8¹ of each builder slide 8 we mount vertically a lifting screw 14 which comes against the bottom of the step rail 6 and lifts the said rail after doffing, as hereafter explained. On the upper end of each vertical guide rod 4 we mount in a pulley bracket 15 a chain pulley 16. From each socket 5 we carry a chain 17 led over the said pulley 16 and downward behind the doffing shaft 12. On this chain 17 we suspend a back balance weight 18 sufficient to sustain the step rail 6. On each builder chain pulley 13 we mount in addition to the builder chain 9 aforesaid a balance relief chain 19 extending to and connected with the step rail back balance weight 18. During spinning, while the doffing shaft 12 is traversing the builder rail 11 up and down, the balance relief chain 17 is slack and inoperative. When, however, the doffing shaft 12 is lowering the builder rail 11 for doffing, the balance relief chain 17 raises the back balance weight 18 of the step rail 6 and thus facilitates the descent of the latter. During spinning the step rails 6 are sustained by a locking bar 20 which is mounted on the low stay rail 2 and which is carried in guides 21 with friction pulleys 22 and can be freely slid endwise. On the locking bar 20 we mount at each socket carrying a step rail a step rail support 23 projecting in front of the locking bar. On the said supports 23 the step rails 6 sit during spinning. At the driving end 24 of the frame we mount a treadle 25 with a back balance weight 26. On depression of the treadle 25 the locking bar 20 is drawn on end, carrying the step rail supports 23 from beneath the sockets 5 leaving the step rails 6 free to descend. The sockets 5 prevent the supports from getting back to normal position until they rise. It will thus be understood that when the frame is stopped for doffing and the doffing shaft 12 disengaged from the traverse motion as hereafter explained and turned so as to lower the builder rails 11 the following results: (a) The builder rails 11 are lowered on to the step rails 6; (b) each of the step rails 6 receiving the weight of the corresponding builder rail 11 and having its back balance weight 18 lifted by the doffing shaft 12 descends; (c) the full bobbins by

their weight slide downward off the spindles. Empty bobbins are then put in their place and the doffing shaft 12 reversed to lift the builder rails 11, which, by the lifting screws 14 described lift the step rails 6 until they are high enough for their supports 23 to slide with the locking bar 20 below the sockets 5 of the step rails 6. The back balance weight 26 on the treadle 25 causes the locking bar 20 to move endwise automatically. In the top spindle rail 1 we mount at a suitable distance apart flier spindles 27 extending down to and supported in the step rails. The said spindles have each a wherve 27¹ with a lower flange fixed thereon below the top spindle rail 1 and are driven by a tape 28 from a tin roller 29 mounted on the frame behind, and parallel with, the top spindle rail. The spindles 27 are supported when running laterally in the top spindle rail 1 and vertically and laterally by the step rails 6. When the step rails 6 are lowered the spindles 27 hang from the top spindle rail 1. On the spindles 27 we place ordinary spinning bobbins 30. To keep the spindles 27 in approximately vertical position when the step rails 6 and builder rails 11 are withdrawn for doffing, so that the said spindles may enter the empty bobbins 30 and also enter the builder rails 11 and the step rails 6 when these are raised after doffing, we mount on the back of the top spindle rail 1 behind each spindle wherve 27¹ a support 31 which extends below the tape 28 and embraces the back of the lower flange of the wherve 27¹ thus the spindle is kept in approximately vertical position as the wherve flange 27¹ is drawn against the support 31 referred to by the tape. The support 31 referred to is just clear of the spindle wherve 27¹ when the spindle 27 is running so that the spindle is drawn slightly off its working position by the tape when its lower support is withdrawn.

We shall now describe the manner in which the doffing shaft is disengaged from the traverse motion when it has to be used to lower the rails for doffing. At the back end 38 of the frame we mount a heart cam 32, a heart cam lever 33, and a chain 34 operating in the usual manner. On the end of the doffing shaft 12 we mount loosely a chain pulley 35 to receive the motion from the heart cam 32 by means of the heart cam lever 33 and chain 34. On the chain pulley 35 we mount a stud and on it a pawl 36 which engages with a ratchet wheel 37 keyed on the doffing shaft 12 so that during spinning the doffing shaft is oscillated by the traverse motion by means of the pawl 36 and ratchet wheel 37 described. When the pawl 36 is lifted clear of the ratchet wheel 37 the doffing shaft is free to lower the rails as before stated. On the back end 38 of

the frame below the pawl 36 above mentioned we mount in a guide bracket 39 a vertical lifter rod 40 which extends downward to the step rail locking bar 20 on which 5 we fix an inclined plane 41 so arranged that the sliding of the locking bar 20 to remove the support 23 from the step rail 6 shall at the same time press the vertical lifter rod 40 upward and lift the pawl 36 out of engagement with the ratchet wheel 37.

We shall now describe the means of revolving the doffing shaft 12 to lower and to raise the rails. On the doffing shaft we key a worm wheel 42 inside the driving end 10 frame 24. On the underside of said worm wheel 42 we mount movably on the framing a worm bracket 43, a worm 44, and a worm shaft 45, the worm bracket and the worm shaft extending inward at right angles to 15 the top spindle rail 1 to a point below the driving shaft 46 of the frame, the driving shaft being carried in bearings on the framing and carrying the tin roller 29 afore referred to. On the outside of the driving 20 end frame 24 we mount on a stud 47 located behind and below the main driving shaft 46 a hand lever 48 which extends to and is supported in a catch 48² at the front of the driving end frame 24. On the hand 25 lever 48 between its back and front supports we form a boss 48¹ carrying a cross shaft 49 disposed horizontal and parallel with the main driving shaft 46. On the inner end of the said boss 48¹ we mount pivotally 30 the inner end 43¹ of the worm bracket 43 afore described. At the junction of the worm bracket 43 and the boss 48¹ of the hand lever 48 we mount a pair of miter wheels 50 and 50¹, one keyed on the worm 35 shaft 45 and the other on the cross shaft 49. On the outer end of the cross shaft 49 we fix a friction pulley 51 which, when driving in one direction or the other, drives the worm shaft 45 and worm 44 above mentioned 40 so as to operate the doffing shaft 12. Below the front end 43² of the worm bracket 43 we mount on the framing a tumbler cam lever 52 by means of which the worker may raise the worm 44 into mesh with the worm 45 45 wheel 42 on doffing shaft 12 or lower it out of mesh. On the main driving shaft 46 we mount a pair of driving pulleys, the fast pulley 53 on the outer end of the main shaft and the loose pulley 54 between the 50 fast pulley and the shaft support on the frame end. At the side of the loose pulley 54 next to the shaft support we fix an upper driving friction pulley 55 and on its side a spur wheel 56. On the main shaft support 55 below the spur wheel 56 we mount upon a stud parallel with main shaft a lower driving friction pulley 57 with a spur wheel 58. Between the upper and lower driving friction pulleys we mount on a stud also carried 60 65 on the main shaft support an intermediate

spur wheel 59 so that when the frame is stopped for doffing and the driving belt is shifted on to the loose pulley 54 the loose pulley will drive the upper pulley 55 and lower driving friction pulley 57 which pulleys are spaced vertically apart about one inch space between their peripheries. We cover the periphery of each friction pulley with leather so as to drive effectively. The friction pulley 51 on the cross shaft aforescribed is of cup shape with a projecting flange 51¹ and is adjusted laterally so as to be driven by the upper driving friction pulley 55 when pressed upward against it and by the lower driving friction pulley 57 which acts on the inner face of the projecting flange of the said driven friction pulley when it is pressed downward. The driven friction pulley thus remains stationary when held clear of the upper 55 and the lower 57 driving friction pulleys. It will thus be understood that when the frame is stopped for doffing and the driving belt is shifted from the fast pulley 53 to the loose pulley 54 the worker performs the following operations: 90 (1) By the operation of the tumbler cam lever 52 he raised the worm 44 into operative relation with the doffing shaft 12; (2) he raises the driven friction pulley 51 to drive the doffing shaft 12 to lift the builder rails 11 95 slightly above their usual traversing height and thus to take the weight of the step rails off their supports 23; (3) he depresses treadle so that the locking bar 20 withdraws the supports 23 from beneath the step rails 100 and at the same time disengages the pawl 36 of the traverse motion from the ratchet wheel; (4) he lowers the driven friction pulley 51 so as to reverse the doffing shaft 12 and to lower the builder rails 11 and the 105 step rails 6. The full bobbins 30 descend with the builder rails 11. When empty bobbins are substituted for full bobbins, the driven friction pulley 51 is raised and the doffing shaft 12 lifts the rails until the step rails are high enough to allow the locking bar to slide automatically until the supports 23 are below the step rails. At the same time the pawl 36 is lowered on to the ratchet wheel 37. The worm 44 is lowered out of 110 operative relation with doffing shaft 12 and the frame is ready to resume spinning.

It will be understood that all the step rails on one side of the frame are interconnected and may be regarded as forming 120 collectively a multi-part rail. So also the builder rails are interconnected and form as it were a multi-part rail movable as a unit.

Having now particularly described and ascertained the nature of our said invention, 125 and in what manner the same is to be performed, we declare that what we claim is:—

1. In spinning, twisting, and like frames, a flier drive shaft, fast and loose belt pulleys thereon, a doffing shaft, and means for 130

- operatively connecting the doffing shaft with the loose pulley to rotate the shaft for doffing during the halt of the flier drive.
2. In spinning, twisting, and like frames, 5 a flier drive shaft, fast and loose belt pulleys thereon, a builder rail, and means operatively connecting the builder rail and loose pulley to lower and lift the builder rail on doffing and resetting the frame during the halt of the flier drive shaft.
3. In spinning, twisting, and like frames, 10 a flier drive shaft, fast and loose belt pulleys thereon, a doffing shaft, a builder rail connected thereto, a worm wheel on the doffing shaft, a worm adapted to be brought into mesh therewith, and means for driving said worm from the loose pulley to rotate the doffing shaft.
4. In spinning, twisting, and like frames, 15 20 a flier drive shaft, fast and loose belt pulleys thereon, a doffing shaft, a builder rail connected thereto, a worm wheel on the doffing shaft, a worm adapted to be brought into mesh therewith, and means for driving said worm in opposite directions from the loose pulley to lower and lift the builder rail.
5. In spinning, twisting, and like frames, 25 30 a flier drive shaft, fast and loose belt pulleys thereon, a doffing shaft, a builder rail connected thereto, a worm wheel on the doffing shaft, a worm adapted to be brought into mesh therewith, and means for driving said worm from the loose pulley to rotate the doffing shaft, said means comprising a friction pulley operatively connected to the driving worm, a pair of coöperating friction pulleys driven by the loose belt pulley, and means for shifting the friction pulley connected to the worm into engagement with 35 40 one or the other of said driven pulleys to rotate the worm in opposite directions.
6. In spinning, twisting, and like frames, 45 50 a spinning spindle, means at the upper end thereof for suspending the same, a step rail detachably engaging the lower end of said spindle, a builder rail arranged above the step rail, a doffing shaft, chains connecting the same to the builder rail, and means for imparting a traverse motion to said doffing shaft to operate the builder rail during the spinning, in combination with means for lowering the builder and step rails to permit doffing from the lower ends of the spindle, and means for raising the builder rail, 55 60 and with it the step rail, into operative position with relation to the spindle, said step rail being supported by the builder rail on said resetting movement, and said means operating through the builder rail, chains and doffing shaft.
7. In spinning, twisting, and like frames, a spinning spindle, means at the upper end thereof for suspending the same, a step rail movable out of engagement with the lower end of the spindle to permit doffing at said end, means for lifting the step rail and means operated from one end of the frame and engaging said rail in its lifted position to hold it in engagement with the lower end of the spindle during the spinning operation. 65 70
8. In spinning, twisting, and like frames, a spinning spindle, means at the upper end thereof for suspending the same, a step rail movable out of engagement with the lower end of the spindle to permit doffing at said end, means for lifting the step rail and means operated from one end of the frame and engaging the under side of said rail in its lifted position to hold it in engagement with the lower end of the spindle during the 75 80 spinning operation.
9. In spinning, twisting, and like frames, a spinning spindle, means at its upper end for suspending the same, a step rail detachably engaging its lower end, a builder rail arranged above the step rail, a doffing shaft operatively connected to the builder rail, means for imparting an oscillating motion to the doffing shaft to raise and lower the builder rail during the spinning operation, means for lifting the step rail to spindle-engaging position, independent means for supporting the step rail during said spinning operation, and means for removing said support and simultaneously breaking 90 95 the traverse motion connection to the doffing spindle to permit the builder and step rails to drop below the lower end of the spinning spindle for doffing the latter.
10. In a spinning, twisting, and like frame, a spinning spindle, means at its upper end for suspending the same, a step rail detachably engaging the lower end of the spindle during the spinning operation but movable downwardly to permit doffing from 100 105 said end, in combination with a flier on said spindle, means for supporting the spindle above the flier and below the top suspension for the spindle to maintain the latter in substantially normal position when disengaged 110 from the step rail.
